UNITED STATES PATENT OFFICE.

ROBERT G. FLEMING, OF BLOOMFIELD, NEW JERSEY, ASSIGNOR TO SMOKADOR MANUFACTURING CO. INC., OF NEW YORK, N. Y., A CORPORATION OF DELAWARE.

GRIPPER FOR SMOKERS' STANDS.

Original application filed February 21, 1925, Serial No. 10,734. Divided and this application filed April 10, 1925. Serial No. 22,056.

This invention relates to improvements in gripping devices and more particularly in some of its aspects to improvements in a gripper particularly adapted as an accessory 5 for smokers' stands for holding cigars, cigarettes etc. in position thereon.

It is a general object of the invention to provide a gripper of the class mentioned which is light, strong and inexpensive in manufacture, and having structural and functional advantages particularly adapting it for the purpose mentioned.

A further object is to provide a practical gripper of the class mentioned with an improved and simple device for attaching it to a support without mutilation of the latter.

A further object is to provide an improved gripper of the class mentioned particularly adapted for firmly holding cigars, cigarettes, etc. and providing for easy insertion of the latter in gripped position, being arranged to avoid injury thereto during insertion and while held thereby.

Other objects will in part be obvious in connection with the following detailed description, and in part pointed out therein.

The invention accordingly comprises the features of construction, combinations of elements, and arrangement of parts, which will be exemplified in the construction hereinafter set forth and the scope of the application of which will be indicated in the claims.

For a complete disclosure of the nature and objects of the invention, reference is had to the accompanying drawing disclosing an illustrative but preferred embodiment of the invention, and in which:

Figure 1 is an elevation of a tiltable self-righting smoker's stand equipped with the improved gripping device;

Fig. 2 is a fragmentary enlarged sectional view of the gripper, parts being shown in elevation;

Fig. 3 is an elevation similar to Fig. 2 and showing the gripper jaws in open position;

Fig. 4 is a section substantially on the line 4-4 of Fig. 2 looking in the direction of the arrows; and

Fig. 5 is a transverse section of one of the gripper jaws.

The subject matter of this application is divided from prior application Serial Number 10,734, filed February 21, 1925.

Referring to the drawing for a detailed description of the embodiment of the invention there shown, a plurality of grippers 10 for cigars, cigarettes and the like are shown as attached to an upper supporting plate or frame piece 11 of the smoker's stand 12. The stand need not be described in detail herein, but reference thereto is made to show the manner of application of the gripper thereto and to indicate its particular utility in connection with the stand. The stand is preferably of the tilting self-righting type, always returning to upright position when tilted by virtue of a relatively heavy weight indicated at 13 and disposed at the bottom of the receptacle part 14 of the stand. A tubular neck 15 extends between the receptacle 14 providing a restricted passageway thereto from an entrance mouth opening through the upper face of the frame plate 11. One or a plurality of the improved grippers are positioned on the frame plate 11 adjacent the entrance mouth so the cigars etc. may be held adjacent said mouth and retained by the gripper in spite of accidental or other tipping of the stand.

The gripper construction embodies a pair of jaws 16 of suitable sheet material preferably sheet brass, being formed for rigidity, lightness and simplicity of construction in channeled cross-section having outwardly directed flanges 17, and juxtaposed webs 18 forming a smooth continuous surface for contacting with the gripped articles, and being provided with opposed concavities for the reception of the articles. Beyond these concavities the free ends of the jaws are provided with upwardly and outwardly divergent surfaces 19 preferably curved and arranged for providing a smooth contact surface for engagement with the entering article and being especially adapted to avoid injury to the latter.

The webs 18 are preferably discontinuous adjacent the lower ends of the jaws and the flanges 17 are extended inwardly toward each other to provide overlapping lugs 20, and a pin 21 extends through these lugs for pivotally connecting the jaws toward the lower ends thereof. The pivoted pin 21 preferably extends across the channel between the opposing flanges of the jaws and a U-shaped yoke or link 22 bows around said pin, its legs extending through an aperture 23 formed through the frame plate 11. At the

opposite side of the plate 11, the legs are yieldingly connected to the plate preferably through the medium of a leaf spring 24 having an opening 25 through which the legs 5 of the yoke extend. A pin 26 passes through the lower ends of the legs for binding the yoke to the spring 24. The ends of the leaf spring are upwardly offset as shown to provide contact surfaces with the frame plate 10 11, thus providing a space between the body of the spring and the lower face of the frame plate.

Lower ends of the jaws 16 are shaped to provide flat surfaces 27 intersecting the outer 15 edges of the jaws at an angle so as to provide fulcrums 28 contacting with the surface of frame plate 11. It will be observed that these fulcrums are disposed at opposite sides of the connecting link 22 being in free supporting contact with the face of the supporting plate 11 and function as rockers for the jaws when the latter are moved to or from gripping position. When the jaws are 20 opened and closed, this rocking action takes place, the pivot pin oscillating toward and away from supporting plate 11 and stressing the spring 24 when the jaws are separated. When an article is placed between the jaws as indicated in dot and dash lines in Fig. 3, 25 the stressed spring 24 tends to cause the jaws to rock toward each other over the fulcrums 28, thus gripping the article in position. Due to the fact that the jaws are constantly urged toward each other, a lighted cigar or 30 cigarette gripped by the jaws will be snuffed or extinguished by action of the latter when the cigar or cigarette burns up to the plane of the gripper jaws. Premature or accidental release of the cigar or cigarette, which 35 would happen if the burning were to continue beyond the plane of the gripper jaws, will thus be prevented.

From the foregoing description, it will be 40 seen that the gripper may be readily attached securely in operative position on the supporting plate without mutilation of said plate, the only modification being the formation of the hole 23 through the plate. When the gripper is attached to the plate by this 45 simple expedient, it operates effectively to perform its described function. The inclined divergent surfaces 19 contact with the article when the latter is lowered into position to be gripped by the jaws, the contact tending to force the jaws apart so the article 50 may enter, or separation of the jaws may be aided by downward and outward manual pressure on the upper end of either jaw. Due to the pivotal connection 21 between the 55 jaws and the positioning of the fulcrums 28 as described, opening movement of one jaw is transmitted to move the other jaw similarly but oppositely, so the two jaws coact in 60 unison both in closing and opening movements.

It will be observed furthermore that the connection described for holding the jaws in cooperative position upon the supporting plate is so arranged as to permit rocking movement of the two gripper jaws as a unit 70 in any direction upon their supporting contact with the supporting plate 11. In such rocking movement, no matter in what direction, it will be yieldingly resisted by means of the resilient connection including the 75 spring 24 by reason of the fact that such unitary rocking movement will cause the spring to be stressed. This function will be clear from Figs. 2 and 4, it being apparent 80 from these figures that during such tilting or rocking movement the combined jaw unit will fulcrum about the outer edge of its base or contact surface so as to cause the link 22 to move upwardly and place the spring 85 under compression. This feature of the gripper is particularly advantageous when it is employed in connection with ash trays or the like for smokers' use as it permits yielding in any direction when a cigar or 90 cigarette is inserted or removed, thus minimizing the danger of injury to the delicate wrappers. Also this cushioning connection permits yielding of the jaws as a unit, as for example, when struck by any external object, thus preventing breaking or injury to 95 the jaws or to the support.

Another attribute of the connection described resides in the fact that the jaws are connected to the supporting plate for swivelling movement, that is, they may 100 rotate upon the supporting link as an axis so as to adjust the plane of the jaws into any desired position. This feature is also particularly advantageous when the gripper is employed in connection with ash trays for 105 smokers' use or the like, where it is desirable as an added convenience to swivelly adjust the gripper so the cigar or cigarette may occupy a definite position or angle with relation to the receiving part of the ash tray, or 110 with reference to any obstacle which may be present upon the tray, such for example as the handle or bail shown adjacent the grippers 10 in Fig. 1.

When the jaws open or close and when 115 they rock together as a unit as above described, it will be observed that the pivot 21 forming the point of attachment for the link 22 oscillates or floats relatively to the supporting plate 11, the link 22 oscillating correspondingly so as to vary the degree of compression of the spring 24. The connection for the jaw unit being located intermediate the extremities of the rocker surfaces and 120 being generally centrally located with reference to said rocker surfaces, and the spring 24 always being under stress, the tendency is 125 to resiliently urge the floating pin 21 toward the supporting plate and thus to urge the jaws toward closed position. For the same 130

reasons the resilient connection described tends to move the jaws as a unit toward upright position when they have been rocked in different directions from said upright position. It will be seen furthermore that when either one of the jaws is urged toward open position, as by engagement of a cigar or the like, the companion jaw will be freed to similar opening movement in the opposite direction, permitting the cigar to pass freely into position to be gripped by the jaws.

Since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new, and desire to secure by Letters Patent, is:

1. In a device of the character described, in combination, a support, a pair of cooperating gripper jaws operatively connected to each other for opening and closing movement, a resilient connection for holding said gripper jaws in operative position upon said support, said resilient connection also cooperating to hold said gripper jaws in contact with said support so that movement of one jaw in opening direction frees the companion jaw to similar but oppositely directed opening movement.

2. In a device of the character described, in combination, a frame plate having an aperture, a pair of cooperative gripper jaws having free diverging ends, a spring bearing against said frame plate on the side thereof opposite from said jaws, and a connecting link between said spring and said jaws passing through said aperture, said spring being stressed for urging said jaws toward gripping position and said connecting link being connected to said jaws at a point thereon movable to and from said frame plate as the jaws close and open.

3. In a device of the character described, in combination, a frame piece having an aperture, a pin at one side of said piece, a spring bearing against said frame piece at the opposite side thereof from said pin, a pair of cooperative pivotally connected gripper jaws mounted on said pin having diverging free ends, a link extending through said aperture, operatively connecting said pin and spring and adapted to stress said spring when the jaws are opened, the bases of said jaws being shaped for rocking move-

ment on said frame piece to cause said pin to rise and fall relative to said frame piece as the jaws open and close.

4. In a device of the character described, in combination, a frame piece having an aperture, a pin at one side of said piece, a spring bearing against said frame piece at the opposite side thereof from said pin, a pair of cooperative pivotally connected gripper jaws mounted on said pin having diverging free ends, a link extending through said aperture, operatively connecting said pin and spring and adapted to stress said spring when the jaws are opened, the bases of said jaws being flat and intersecting their sides at an angle.

5. In a device of the character described, in combination, a frame plate having an aperture, a pin at one side of said plate, a spring bearing against said plate at the side thereof opposite said pin, a pair of cooperative gripper jaws mounted for pivotal movement on said pin and having diverging free ends, a link connected to said pin and extending through the aperture in said frame plate and through an aligning aperture in said spring and connected to the latter, and fulcrums on said jaws contacting with said frame plate at opposite sides of said link.

6. In a device of the character described, in combination, a frame piece having an aperture, a pin at one side of said frame piece, a pair of cooperative oscillatable gripper jaws connected to said pin and having flattened bases providing spaced fulcrums contacting with said frame piece, a leaf spring bearing against said frame piece at the side thereof opposite said pin, and a link connected to said pin and said spring and extending through said aperture.

7. In a device of the character described, in combination, a supporting plate having an aperture, a pair of cooperative gripper jaws pivotally connected together and resting on said supporting plate and having upwardly diverging free ends, and a link connected to said jaws extending through said aperture and resiliently connected to said supporting plate opposite said jaws.

8. In a device of the character described, in combination, a supporting plate, a pair of cooperative gripper jaws each being channeled in cross-section with outwardly directed flanges and adjacent web sections, said jaws being pivoted together and having divergent contact surfaces at the free ends thereof, and a connection from said jaws to said supporting plate holding said jaws in contact with said plate and thereby tending to urge said jaws into cooperative gripping relation.

9. In a device of the character described, in combination, a supporting plate, a pair of cooperating gripper jaws each being channeled in cross-section with outwardly direct-

ed flanges and adjacent web sections, said flanges being shaped at their ends to form spaced fulcrums contacting with said supporting plate and being pivotally connected together, and means for connecting said jaws to said plate.

10. In a device of the character described, in combination, a supporting plate, a pair of cooperating gripper jaws each being chan-

neled in cross-section with outwardly directed flanges and adjacent web sections, said flanges being shaped at their ends to form spaced fulcrums contacting with said supporting plate, overlapping lugs extended 15 from said flanges inwardly from said fulcrums, a pin connected to said lugs for pivotally connecting the jaws, and a connection between said pin and said supporting plate extending through the latter.

20. 11. In a device of the character described, in combination, a pair of gripper jaws movable toward and away from each other, a support for supporting said jaws and a resilient connection from said jaws to said 25 support and including an oscillatable connecting link, said resilient connection normally holding the jaws in contact with said supporting plate and thereby tending to urge the jaws into cooperative gripping position 30 and constituting the sole attaching means for attaching the jaws upon said support.

35. 12. In a device of the character described, in combination, a supporting plate, a pair of cooperative pivotally connected gripper jaws outstanding from the supporting face of said supporting plate and each of which is provided at its base with a supporting 40 rocker surface in rocking supporting contact with said supporting face being rockable thereon to and from gripping position relatively to each other, and a resilient connection from said jaws to said supporting plate positioned intermediate said rocker 45 surfaces tending to urge said rockable jaws into gripping relation.

50. 13. In a device of the character described, in combination, a support, a gripper unit including a pair of cooperative gripper jaws operatively connected together for opening and closing movement, said unit having a 55 rocker bearing contact surface in free supporting contact with said support whereby said gripper unit may rock as a unit in different directions, and a resilient connection for holding said gripper unit upon said support, said resilient connection being centrally positioned with relation to said rocker surface so as to yieldingly cushion said 60 gripper unit against unitary rocking movement in different directions.

14. In a device of the character described,

in combination, a support, a gripper unit including a pair of gripper jaws operatively connected together for opening and closing movement, said unit having a supporting contact surface in free supporting contact with said support and a resilient connection for holding said gripper unit upon said support, said connection being positioned centrally of said contact surface and connecting the gripper unit for swiveling movement upon said support.

15. In a device of the character described, in combination, a supporting plate, a pair of cooperative gripper jaws operatively connected to each other and being in free supporting contact with said supporting plate for rocking movement thereon as a unit in different directions, and a connection resiliently holding said gripper jaws in cooperative position on said supporting plate and yieldingly cushioning them against said unitary rocking movement, said connection including a link extending through an aperture in said supporting plate so as to support the jaws for swiveling movement as a unit upon said link as an axis.

16. In a device of the character described, in combination, a gripper unit including a pair of gripper jaws operatively connected together for opening and closing movement, a support for said gripper unit and a single resilient connection yieldingly holding said gripper unit in contact with said support thereby to yieldingly urge said jaws into cooperative gripping relation.

17. In a device of the character described, in combination, a support, a gripper unit including a pair of gripper jaws operatively connected together for opening and closing movement, each of said gripper jaws having a supporting contact surface in free supporting contact with said support, said contact surfaces forming rocker bearings for rockably supporting the jaws, and a stressed yielding connection from said support to said gripper unit for holding said unit upon said support, the line of stress of said connection being positioned intermediate the outer limits of said rocker bearings so as to urge said jaws to move upon their bearings into cooperative gripping relation.

18. In a device of the character described, in combination, a support, a gripper unit including a pair of gripper jaws operatively connected together by a floating pivotal connection and having supporting contact surfaces spaced at opposite sides of said pivotal connection and in free contact with said support, and a resilient supporting connection from said floating pivot to said support.

In testimony whereof I affix my signature.

ROBERT G. FLEMING.
